UNITED STATES PATENT OFFICE

REX C. DARNELL, OF ROYAL OAK, MICHIGAN, ASSIGNOR OF ONE-THIRD TO HAROLD B. PUTNAM, OF DETROIT, MICHIGAN, AND ONE-THIRD TO FRANK L. MUNSON, OF WARREN, MICHIGAN

SOUND REGENERATING APPARATUS

Application filed December 28, 1925. Serial No. 77,946.

This invention relates to sound regenerating apparatus and is particularly directed to the attainment of a direct propagation, in free air, of self sustaining sound waves substantially corresponding in intensity and quantity, as well as in timbre and mellow-ness and other qualities, to the originally produced sound waves. The invention relates more particularly to a reproducing or 10 sound regenerating device of the cone dia-phragm or tympanum type.

In the present day development of this art as now extensively commercially ex-ploited many types of cone diaphragms have 15 been produced. These devices show a marked similarity in design as well as in efficiency as regards tone quality and faith-fulness in reproduction but in the majority of such devices notable defects are apparent.

20 Exhaustive study of the problems presented has disclosed the causes and fundamental deficiencies in these heretofore known types which result in their inefficient operation.

In cone tympanums as heretofore pro-25 duced the diaphragm was so mounted with reference to its supporting frame that the movements imparted thereto by the sound vibrated element produced a buckling of the diaphragm adjacent its peripheral sup-

30 port. It has been determined that this is the result of a too rigid or nonflexible mounting of the diaphragm or tympanum. This rigidity of construction resulted first from the angle of projection of the cone

35 with reference to its supporting frame and secondly because of the non-flexibility of the connection between the tympanum and the tympanum support. Efficiency in tonal quantity and quality as well as faithfulness 40 in reproduction is therefore best obtained with a tympanum capable of freely vibrat-ing both forward and aft.

Another structural feature essential to effi-cient operation is the connection between 45 the diaphragm operating element and the tympanum. While it is customary to form the tympanum of a light vibratile material nevertheless a metallic connection between the diaphragm actuating element and the 50 tympanum will cause thin and harsh metal-

lic tones. It is therefore essential that the connection between the diaphragm actuating element and the tympanum be of a material which functions as a tone modifier, deadener or rattle preventative whereby the mellow-ness and richness of the tones is maintained. For accomplishing this it is essential that some non-metallic substance be employed in this connection.

55 In conical tympanums as now commer-cially produced it is almost universally the prac-tice to connect the diaphragm actuating ele-ment to the tympanum at the apex thereof. While such constructions operate more or less efficiently nevertheless the relatively 60 weak and minute vibrations are transmitted to the tympanum at the point of its greatest rigidity. In conical tympanums the most flexible point on any radial line drawn from the apex to the periphery is midway or in-65 termidiate between the apex and the periph-ery of the cone and consequently if the sound vibrations are transmitted to the tym-pa-num at such a point, or in conical dia-phragms on a circumferential line interme-70 diate the apex and periphery, then the dia-phragm will function more responsively as the vibrations are imparted thereto at its most flexible circumferential point.

75 It has also been found that it is most effi-cient to rigidly support the tympanum peripherally but that mellow-ness of tone and faithfulness in reproduction is best obtained first when the tympanum supporting frame is of a non-metallic material and second, 80 when such supporting frame is peripherally spaced with reference to the effective dia-meter of the tympanum.

85 This invention has, therefore, among its objects to produce a tympanum or cone type diaphragm having incorporated therein 90 structure wherein the aforementioned ob-jections are eliminated and the advantages outlined above best obtained. To this end the invention contemplates a tympanum 95 having formed either integrally therewith or attached thereto a plurality of peripheral pro-jections by means of which the tym-pa-num is connected to a non-metallic periph-erally spaced supporting frame. The com-100

bined width of these projections is only fifty percent or less of the effective outside diameter of the tympanum, these projections furthermore being extended perpendicularly to the axis of the conical tympanum or angularly with reference to the walls of the cone. Furthermore the invention contemplates the use of non-metallic material in the connection between the actuating element and the diaphragm and also contemplates the use of a relatively inverted cone shaped member rigidly connected to the conical tympanum on a circumferential line preferably intermediate the apex and periphery of the tympanum, the diaphragm actuating element in such a construction being connected to the apex of this inverted cone.

Various other objects, advantages and novel details of construction of this invention will be made more apparent as this description proceeds especially when considered in connection with the accompanying drawings wherein:

Fig. 1 is a side elevation of a tympanum constructed in accordance with this invention.

Fig. 2 is a front elevation thereof.

Fig. 3 is an enlarged vertical fragmentary section through the tympanum.

Fig. 4 is a fragmentary sectional elevation taken substantially on the plane indicated by line 4-4 in Fig. 3, and

Fig. 5 is a view similar to Fig. 3 of a slightly modified form of construction.

Referring now particularly to the drawings wherein like reference characters indicate like parts it will be noted that there is illustrated a conical tympanum or diaphragm 10 constructed preferably of a light vibratile material and supported adjacent its periphery by means of a frame 11 and a binding ring 12. The frame 11 is connected to a supporting arm 13 preferably by means of a plurality of radial arms 14. The effective outside diameter of the tympanum 10 is indicated by the reference character 15, it being noted that this peripheral line 15 of the tympanum is spaced from the inside edge of the supporting frame 11. Supporting connection between the tympanum 10 and frame 11 is accomplished by means of a plurality, that is, two or more projections 16, which in the form of construction herein shown are made integrally with and a part of the tympanum 10. However, these extensions or projections may obviously be formed separate and connected to the periphery of the tympanum. It is essential, however, that the total width of the combined projections 16 not exceed and be preferably less than fifty percent of the effective periphery of the tympanum. Furthermore it is of extreme importance that these extensions 16, be arranged perpendic-

ular to the axis of the tympanum or, in other words, extend radially from the tympanum axis and at an angle to the plane of the wall of the conical tympanum 10, such as clearly shown in Fig. 3. These extensions or projections 16 are tightly engaged and rigidly supported by being clamped between the frame 11 and clamping ring 12.

The supporting frame 11, clamping ring 12 and arms 14 are all preferably formed of a non-metallic material and as mentioned the supporting frame and tympanum are so designed that the effective outside diameter of the tympanum indicated by the line 15 is spaced from the inside periphery of the supporting frame 11. By reason of this latter construction and furthermore owing to the readily flexible extensions angularly arranged with reference to the wall of the tympanum vibrations transmitted to the tympanum will cause a free vibration of the tympanum both fore and aft or in both directions, without liability of any distortion of the tympanum such as a buckling thereof adjacent its periphery. During the vibratory movements of the tympanum the displacement thereof fore and aft is compensated for by the flexing of the projections or extensions 16 along that part of these extensions which extends from the inner diameter of the frame 11 to the outer peripheral line 15 of the tympanum 10. An exaggerated indication of this compensating movement of the extensions 16 is indicated in Fig. 5.

The features of this invention thus far described are common to both forms of construction herein illustrated, as will be clearly apparent from a comparison of Figures 3 and 5. Likewise the connection between the diaphragm actuating element and either the tympanum 10 or the inverted intermediate cone or actuating member yet to be described, is also identical. A description of this invention follows.

The diaphragm actuating element 17 which is actuated by the sound vibrated mechanism, which latter mechanism may be either mechanical as in phonographs or electrical as in radios, preferably extends coincident with the axis of the tympanum as clearly illustrated in Figures 3 and 5. This element 17 is externally threaded as indicated at 18 to receive spaced clamping nuts 19 and 20. Fitments 21 engage the apex of the cone and clamp the same therebetween, these fitments being maintained in clamping position with reference to the cone by means of a compressible non-metallic sleeve of material 20 arranged on the element 17. This sleeve has one end thereof compressed by means of the nut 20 to form a circumferential shoulder 23 which abuts the ends of the fitments to thus urge the outer fitment 21 into clamping engagement. The other end 130

of sleeve 22 is compressed by means of the nut 19 to form a circumferential shoulder 24 which bears against the inner fitment 21 in the purview of the accompanying claims. to urge the same into clamping position. It

5 should be noted that the diameter and wall thickness of the sleeve 22 is such that the fitments 21 are spaced from the element 17 as well as from the nuts 19 and 20 so that under no circumstances will there be any 10 surface contact between these parts. This sleeve of non-metallic material 22 acts as a tone modifier and prevents thin metallic and harsh tones.

The circumferential line indicated at 15 is substantially intermediate the apex 26 and periphery 15 of the conical tympanum 10 and at this point I propose connecting the base or periphery 27 of a secondary actuating member 28 formed preferably of 20 light non-vibratile material. This member

28, here shown as a cone, is inverted relative to the conical tympanum 10 and has its apex consequently extending in an opposite direction to the apex 26. The body of the member 28 is preferably cut away at a plurality of points as indicated at 29 so as to make this cone of a substantially skeleton or perforated nature maintaining however, both the outer periphery and the inner periphery

30 adjacent the apex preferably unbroken or continuous. The diaphragm actuating element 17 is connected to the apex of cone 28 by the fitments 21 as previously described. The openings 29 in the cone 28 permit sound 35 waves caused by a vibration of the tympanum between the circumferential line 25 and the apex 26 to freely pass backwardly through this member 28. While the member 28 is shown and described as substantial-

40 ly cone-shaped it will be apparent that constructions involving, for instance, a plurality of converging arms or a skeleton structure having its periphery and apex continuous and connected by arms, may be utilized with 45 equal effectiveness.

The construction just described is conducive of greater sensitiveness because the vibrations are transmitted through the member 28 to the conical tympanum 10 at a circumferential point spaced between the apex and effective outer diameter of the tympanum at a point where the tympanum is most flexible. Consequently tonal quality and quantity is assured.

50 55 In describing the embodiments of the invention illustrated in the drawings numerous details not essential to the accomplishment of the objects of this invention have been described and it will be readily apparent that these details may be altered without departing from the spirit and scope of this invention and furthermore that many of the more essential features of the invention may also be changed without sacrificing 60 any of the advantages of the invention and

What I claim as my invention is:

1. In an acoustical device, a tympanum support, a tympanum and spaced peripheral projections on said tympanum and means for rigidly connecting the ends of said projections to said support, the total circumferential width of said projections occupying 70 fifty percent or less of the effective outside periphery of said tympanum.

2. In an acoustical device, a tympanum support, a conical tympanum and peripheral extensions, perpendicular to the axis of the 80 tympanum and means for rigidly connecting the ends of the same to said support, the total width of said extensions being fifty percent or less than the effective outside periphery of said tympanum.

3. In an acoustical device, a circular tympanum support, a conical tympanum and peripheral extensions, perpendicular to the axis of the 90 tympanum rigidly connected to said support, the total width of said extensions being fifty percent or less than the effective outside periphery of said tympanum.

4. In an acoustical device, a tympanum support, a conical tympanum and peripheral 95 extensions, perpendicular to the axis of the tympanum and extending from the effective outside periphery thereof for connecting same to said support, the total width of said extensions being fifty percent or less than the 100 effective outside periphery of said tympanum.

5. In an acoustical device, a circular tympanum support, a conical tympanum and readily flexible peripheral extensions, perpendicular to the axis of the 105 tympanum rigidly connected to said support, the total width of said extensions being fifty percent or less than the effective outside periphery of said tympanum.

6. In an acoustical device, a conical diaphragm, a plurality of peripheral extensions on said diaphragm and a support rigidly engaging said extensions and peripherally spaced from the effective outside periphery 115 of said diaphragm, the total width of said extensions being fifty percent or less than the effective outside periphery of said diaphragm.

7. In an acoustical device, a substantially 120 conical tympanum, and a relatively inverted substantially conical actuating member secured to said tympanum and affording means for connection to a vibration transmission element.

8. In an acoustical device, the combination with a conical tympanum, of a relatively inverted substantially cone-shaped member connected to said tympanum at a point spaced from the apex of said tympanum,

- the vibrations being conducted to said tympanum through said inverted cone-shaped member.
9. In an acoustical device, the combination with a conical tympanum, of a relatively inverted cone-shaped member secured thereto at a circumferential point spaced from the apex of said tympanum, and a vibration transmission element connected to said inverted cone-shaped member.
10. In an acoustical device, the combination with a conical tympanum, of a relatively inverted cone-shaped member peripherally rigidly secured thereto at a circumferential point spaced from the apex of said tympanum, and a vibration transmission element connected to said inverted cone-shaped member.
11. In an acoustical device, the combination with a conical tympanum, of a relatively inverted perforated cone secured thereto at a circumferential point spaced from the apex of said tympanum, and a vibration transmission element connected to said inverted cone.
12. In an acoustical device, a conical tympanum, a relatively inverted cone having its periphery connected to said tympanum at a circumferential line intermediate the apex and periphery of said tympanum, and a diaphragm actuating element non-metallically connected to said inverted cone.
13. In an acoustical device, a conical tympanum, a relatively inverted cone having its periphery connected to said tympanum at a circumferential line intermediate the apex and periphery of said tympanum, and a diaphragm actuating element non-metallically connected to the apex of said inverted cone.
14. In an acoustical device, a conical tympanum, a relatively inverted cone secured at its periphery to said tympanum on a circumferential line spaced from the apex of said tympanum, a diaphragm actuating element attached to the apex of said inverted cone, readily flexible spaced extensions on the periphery of said tympanum located perpendicular to the axis thereof, a non-metallic frame rigidly engaging said extensions for supporting said tympanum, said frame being peripherally spaced from the effective periphery of said tympanum.

In testimony whereof I affix my signature.

REX C. DARNELL.
